UNITED STATES PATENT OFFICE.

CHARLES HAYS, OF ERIE, PENNSYLVANIA, ASSIGNOR TO THE HAYS MANUFACTURING COMPANY, OF SAME PLACE.

HYDRANT.

SPECIFICATION forming part of Letters Patent No. 416,104, dated November 26, 1889.

Application filed May 28, 1889. Serial No. 812,418. (No model.)

To all whom it may concern:

Be it known that I, CHARLES HAYS, a citizen of the United States, residing at Erie, in the county of Erie and State of Pennsylvania, have invented certain new and useful Improvements in Hydrants; and I do hereby declare the following to be a full, clear, and exact description of the invention, such as will enable others skilled in the art to which it appertains to make and use the same.

This invention relates to hydrants; and it consists in certain improvements in the construction of the box or case of the same, as will be hereinafter fully set forth, and pointed out in the claims.

My invention is illustrated in the accompanying drawings, as follows:

Figure 1 is an elevation view of the pipes of the hydrant, with the case in vertical section. Fig. 2 shows the case in elevation. Fig. 3 shows the case and pipes in transverse section and the parts of the case separated. Fig. 4 shows the case and pipes in transverse section and the parts of the case joined together. The lines xx in Figs. 1 and 2 show the transverse line of section.

Heretofore hydrant cases or boxes when made of cast-iron have been made of one piece in the form of a tube. In the construction shown the case is made of two longitudinal sections A A', which are secured together by bolts or rivets a^4 , which may pass through holes a^3 in the central part of the castings, as in Figs. 2 or 4, or they may pass through ears a^2 , as shown in Figs. 1 and 3. The two parts of the case are fluted, so as to form when brought together two spaces a and a' for the reception of the pipes B and B', respectively, and at the top of the space a there is a boss

a^5 , which embraces the nozzle B² on the pipe 40 B, and at the top of the space a' there is a boss a^6 , which forms a bearing for the key-stem K. The two parts when clamped upon the pipes B B' firmly secure them in place and keep them parallel. This construction 45 is much cheaper and better than an integral tube, first, because it can be made with less iron and less work; second, because it can be applied to the pipes much quicker, and, third, because it is more convenient to apply, as the 50 pipes and valves can all be put together and tested, and the case can then be applied without disconnecting any of the parts of the hydrant. Another advantage is, that the hydrant when finished is lighter and easier to 55 transport, and it is less bulky and more ornamental.

What I claim as new is—

1. In a hydrant, the combination, with the pipes B and B', of a surrounding case formed 60 of two longitudinal sections A A', each of which is fluted, so as to form spaces a and a' , to receive and hold the said pipes B B', substantially as and for the purpose set forth.

2. In a hydrant, the combination, with the 65 pipes B B', nozzle B², and key-stem K, of a case consisting of the two longitudinal sections A A', formed with spaces a and a' , for embracing the pipes B and B', and bosses a^5 and a^6 , for embracing the nozzle B² and key- 70 stem K.

In testimony whereof I affix my signature in presence of witnesses.

CHARLES HAYS.
